UNITED STATES PATENT OFFICE.

GEORGE J. DAY, OF BUFFALO, NEW YORK.

OVEN THERMOMETER.

Application filed August 19, 1921. Serial No. 493,768.

To all whom it may concern:

Be it known that I, GEORGE J. DAY, a citizen of the United States, residing at Buffalo, in the county of Erie and State of New York, have invented new and useful Improvements in Oven Thermometers, of which the following is a specification.

This invention relates to a thermometer which is more particularly adapted for use 10 on oven doors and the like, having one or more window panes through which the condition of the articles placed in the oven may be observed from time to time.

Its chief object is the provision of a detachable thermometer of this character capable of being readily applied to and removed from ordinary or existing oven doors, without in any way altering their construction.

Another object of the invention is to provide a removable thermometer which is simple and compact in construction and which can be manufactured at a low cost.

A further object is to provide the thermometer with an improved pointer or indicator which is so mounted as to practically eliminate friction, thus insuring its free and reliable action under all conditions.

In the accompanying drawings:

Figure 1 is a front view of an oven showing one form of my improvement applied thereto. Figure 2 is a fragmentary horizontal section, on an enlarged scale, on line 2—2, Fig. 1. Figure 3 is an enlarged fragmentary vertical section on line 3—3, Fig. 1. Figure 4 is an enlarged fragmentary rear view of the oven door showing the thermometer in position thereon. Figure 5 is a perspective view of the thermometer. Figure 6 is an enlarged sectional elevation of the dial plate and its pointer or indicator-hand. Figure 7 is a perspective view of a modified form of the improvement. Figure 8 is a rear view of a different style of oven door, equipped with said modified form of thermometer.

Similar characters of reference indicate corresponding parts throughout the several views.

In the embodiment of the invention shown in Figs. 1—6, the thermometer is shown as applied to a portable oven 10 of well-known construction having a swinging door 11 provided with a transparent panel or window pane 12 of glass or other appropriate material. The pane is confined in the usual

groove or channel, which in the example illustrated in the drawings, is formed between the frame of the door and the flanged or rabbeted back-strips 13 suitably secured to the inner side of said frame, as shown in Figs. 2, 3 and 4.

Detachably mounted on the inner side of the oven door and in one corner thereof, is the improved thermometer which preferably comprises a rectangular base or body portion 14 of sheet metal or other appropriate material having suitable ears, flanges or projections 15, 16 at adjacent upright and horizontal edges thereof, adapted to be inserted between the flanged back-strips 13 and the rear side of the window pane, whereby the base is reliably held in place on the door but at the same time removable therefrom. As shown in Figs. 2, 3 and 5, 70 these flanges, which are preferably formed integrally with said base, are raised or offset forwardly therefrom and substantially parallel to the plane thereof, so as to space the base sufficiently from the back of the window pane to receive the remaining elements of 75 the thermometer. For this purpose, the flanges 15 and 16 are connected with the base by webs 15^a, 16^a, arranged substantially at right angles to the base.

17 indicates the dial or indicator plate of the thermometer suitably secured to the front side of the base 14 and bearing on its face a substantially semi-circular graduated temperature scale 18 which is traversed by 90 a hand or pointer 19. In the preferred construction shown, the dial plate is held against vertical displacement by retaining lips 20, 21 formed on the base and bent around the upper and lower edges of the dial 95 plate. Horizontal displacement of the latter is prevented by the web 15^a at one edge of the base and by a forwardly bent retaining flange 22 at its opposite edge.

Any suitable thermal means may be employed for controlling the movement of the pointer 19, but as shown in the drawings, particularly Figs. 2, 3 and 6, these means preferably comprise a forwardly extending post or arbor 23 rigidly secured to the dial 100 plate at the axis of the scale, and a spiral or volute thermostatic element 24 fastened at its inner end to said post, and carrying the pointer at its free outer end to which the pointer is suitably secured. This thermostatic element which is constructed of any suitable thermostatic material, expands and

contracts in response to variations in temperature, moving the pointer over the dial in one direction or the other. To protect and conceal the spring, a cover or guard plate 25 may extend over the front side thereof, said guard preferably projecting inwardly from the retaining flange 22. If desired, the front end of the post 23 may pass through said guard-plate and be upset 10 on the outer side thereof, as shown in Fig. 2, to brace and stiffen the post. Clearance is provided on both sides of the spiral spring to permit its free expansion and contraction without friction in response to variations in 15 temperature.

By this construction and arrangement of the thermal spring and the pointer, bearings and other friction-producing parts are eliminated, thus rendering the thermometer very 20 accurate and sensitive to thermal changes. Furthermore, the construction is exceedingly simple and there are no parts which are liable to clog up with grease or otherwise get out of order.

25 To apply the thermometer, the oven door is opened and the thermometer is thrust into the lower inside corner of the door with the attaching flanges 15, 16 thereof inserted between the adjacent marginal portions of 30 the window-pane and the back-strips 13 of the door, in which position the thermometer is reliably held and exposed to view. As the attaching flanges are comparatively thin and the flanges of said back-strips are flexible 35 or resilient, the thermometer can be frictionally interlocked with the door in this manner without difficulty. The thermometer can be as readily removed by simply withdrawing its attaching flanges from the 40 corner of the door, in an obvious manner.

In the modification of the improvement shown in Figs. 7 and 8, the base 26 is provided at either side with upright attaching flanges 27 and at its bottom with a horizontal attaching flange 28. This form of 45 the invention is designed more particularly for a door of the type shown in Fig. 8, having on its inner side a plurality of windows or transparent panels 29 confined in substantially U-shaped guide frames 30. In applying this modified form of the improvement to a door of this character, the thermometer is inserted in the open upper end of one of the guide-frames on the inner 50 side of the door and forced to the lower end thereof, the upright attaching flanges 27 engaging under the upright portions of said guide frame and the horizontal attaching flange 28 under the base portion of said 55 frame.

60 It will be noted that inasmuch as the embodiment of the invention shown in Figs. 1-5, is provided at two adjacent sides or edges with corner-attaching flanges, it is 65 applicable to a door of the type illustrated

in Fig. 8, as well as to the style of door shown in Fig. 1.

The removable character of the thermometer not only permits its ready application to existing oven doors of various kinds, but 70 also enables it to be removed for cleaning its dial from time to time.

I claim as my invention:

1. A detachable thermometer for an oven 75 door having a window pane, said thermometer comprising a base having means mounted thereon for indicating temperatures, the base having a marginal attaching portion constructed to enter between the window pane and the frame of the oven door. 80

2. A detachable thermometer for an oven door having a window pane, said thermometer comprising a base having means mounted thereon for indicating temperatures, the base having an attaching flange arranged at its edge for engagement with the oven door, said flange being offset forwardly from said base and substantially parallel to the plane thereof. 85

3. A detachable thermometer for an oven 90 door having a window pane, said thermometer comprising a substantially rectangular base having means mounted thereon for indicating temperatures, the base having marginal attaching flanges projecting from different edges thereof and arranged to engage corresponding sides of the oven-door groove which receives said pane. 95

4. A detachable thermometer for an oven 100 door having a window pane, said thermometer comprising a substantially rectangular base having means mounted thereon for indicating temperatures, the base having upright and horizontal attaching flanges arranged at adjacent edges thereof, said flanges being offset forwardly from said base 105 and substantially parallel to the plane thereof and adapted to enter between the window pane and the frame of the oven door. 110

5. A detachable thermometer for an oven 115 door having a window pane, said thermometer comprising a substantially rectangular base having means mounted thereon for indicating temperatures, the base having marginal attaching flanges projecting from different edges thereof and arranged substantially parallel to the plane of said base and webs connecting said flanges with the base and arranged substantially at right angles to the base, said flanges being adapted to enter between the window-pane and the frame of the oven-door. 120

6. The combination with an oven door 125 having a window-pane and retaining means therefor, of a removable thermometer arranged on the rear side of said door and having attaching means inserted between the said window-pane and said retaining means. 130

7. The combination with an oven door having a window-pane and a retaining groove therefor, of a detachable thermometer arranged on the rear side of said door and including a base having a marginal attaching flange inserted between said window-pane and the rear wall of said retaining groove.

8. An oven thermometer, comprising a base provided on its face with a non-rotary

forwardly-projecting post and with a dial having a curved temperature-scale arranged concentrically with said post, a volute thermostatic element arranged on the outer, dial-side of said base and having its inner central portion fastened to said post, and a pointer fastened to the free outer end of said thermostatic element and traversing said dial. 15

GEORGE J. DAY.

Certificate of Correction.

It is hereby certified that in Letters Patent No. 1,458,168, granted June 12, 1923, upon the application of George J. Day, of Buffalo, New York, for an improvement in "Oven Thermometers," errors appear in the printed specification requiring correction as follows: Page 2, lines 4 and 17, for the word "spring" read *element*, and line 12, for the words "spiral spring" read *thermostatic element*; and that the said Letters Patent should be read with these corrections therein that the same may conform to the record of the case in the Patent Office.

Signed and sealed this 17th day of July, A. D., 1923.

[SEAL.]

WM. A. KINNAN,
Acting Commissioner of Patents.
